UNITED STATES PATENT OFFICE.

WARREN J. FRETZ, OF ST. PAUL, MINNESOTA.

EAR TAG.

Application filed August 16, 1923. Serial No. 657,713.

To all whom it may concern:

Be it known that I, WARREN J. FRETZ, a citizen of the United States, residing at St. Paul, in the county of Ramsey and State 5 of Minnesota, have invented a new and useful Improvement in Ear Tags, of which the following is a specification.

My invention relates to ear tags which are particularly adapted to be used in marking 10 cattle with certain identification and which are inserted through the animal's ear in a particular manner with one operation so that the tag will be held firmly in place where it can be readily inspected.

15 The invention includes a particularly designed tag, which, owing to its peculiar shape, accomplishes the desired results in fastening and permanently securing the tag in place. It is very desirable to provide a 20 tag which is so made that it will remain firmly positioned within the ear after it has been placed, without binding at the point of piercing the ear and yet not free to move around or back and forth so that it 25 will be firmly held in position after the ear is healed at the point where the tag extends through the ear. The particular shape of my tag is of marked importance and for the reason that it permits the animal's ear to 30 swell where it has been pierced without causing the same to slough away so that the tag would be loose when the ear had healed up. Many tags are not practical because of the sloughing of the ear caused by the construction 35 of the same and therefore they readily become entirely disengaged from the ear. For this reason many cattle can be observed where a portion of the ear is torn away due to the improper connection of the tag with 40 the ear.

My invention is a part of and is a division 45 of my United States application number 648,492, filed June 29, 1923, wherein an applying device is illustrated which features with the particular shape of my tag to permit the same to be attached to the ear by a single operation with one hand as fully disclosed in my hereinbefore mentioned application.

50 In the drawings forming part of this specification:

Figure 1 is a perspective view of my tag in closed position, not attached.

Figure 2 is a perspective view of the tag 55 in open position.

Figure 3 is a section of a portion of an

animal's ear illustrating my tag attached thereto.

Figure 4 is a view of one side of my tag.

Figure 5 is a view of the other side of 60 the tag.

The drawings illustrate the tag A made of flat wire tag metal which is cut in suitable lengths for each tag.

The body of the tag is formed with a 65 straight flat side 10 which is connected to the other side 11 of the body portion by the curved end 12 so that the portion 11 extends at an angle from the part 10.

The portion 10 carries the closing and 70 sealing portion of the tag B at the opposite end to the curved portion 12 which is formed with a curved portion 13 from which extends the straight portion 14 and projecting from the portion 13 is the sealing 75 end 15. Interposed between the portions 14 and 15 is formed a recess or cut 16 which is stamped into the member A when it is being formed so as to form a weakened portion along the cut 16 to permit the sealing end 15 to bend into closing position when the tag A is attached to the animal's 80 ear C.

The tag A is formed with a score line 85 18 extending across the width of the tag at the adjoining point of the curved portion 12 and interposed between the parts 10 and 11 of the tag. This score or recess may be similar to the recess 16 so as to form a weakened portion in the tag to permit the 90 same to bend into the desired shape when the tag is attached to the ear C.

The tag A is formed from a single piece 95 of flat ear metal wire which has the proper consistency so as to be formed in the desired shape. The flat wire used in making my tag is stamped on its outer sides with the desired data and is formed into the shape illustrated in Figure 2, after the material has been scored or cut at 16 between the 100 portions 14 and 15 and at 18 between the portion 12 and the portion 10. The tag A, in this form, is ready to be inserted into my tag mentioned by a single operation.

When the tag A is applied to the ear C, 105 the applying device pierces the ear to form an opening 17 through which the end B of the tag A readily passes and the portions 11 and 14 are brought into the position illustrated in Figure 3 with the sealing end 15 110 into engagement with the free end of the portion 11, the tag bending at a pronounced

angle along the cut 16 so that the sealing end 15 will extend in line with and in engagement with the free end 19 of the tag A. When the tag A is positioned as illustrated in Figure 3, the curved end 12 extends around the edge 20 of the ear C, with the sides 10 and 11 in close relation to the sides of the ear at the point of connection with the portion 12, the curved portion 12 extending 10 at an angle from the cut or score line 18 from the portion 10 so that the tag A is formed to the shape of the thin outer edge of the ear with the outer portion 10 extending flat against the outer face of the ear C. 15 The curved portion 13 extends through the opening 17 formed in the ear, while the portion 14 is positioned to extend at an angle from the curved portion 13 and the sides 10 and 11 to form the open or engaged 20 space 21 at this end of the tag A between the sides 10 and 11 as illustrated in Figure 3 of the drawing. The space 21 provided, together with the peculiar angular extension of the portion 14 permits the tag A to be 25 attached in a manner so that the swelling of the ear at the cut or piercing 17 is accommodated without so called sloughing of the ear by reason of the swelling where the ear is pierced and when the tag is of a formation 30 so that the sides of the same extend parallel and in close proximity to the sides of the ear. Many other tags have been used where the sides of the same lie flat and close against the sides of the ear. Invariably, 35 these tags will slough in the ear, which is natural because of the tag having no open space to permit the ear to swell. In such a tag, the swelling causes a pressure or sloughing on the opening pierced in the ear 40 and has a tendency to push the tag out which engages the opening pierced in the ear so that, when the ear heals, the opening has enlarged to such an extent that the tag will hang free in the ear and, as soon as it gets 45 caught on anything, will be readily torn out more and more so that eventually the tag will tear right out of the ear.

My tag A forms a shape with the side 10 extending straight and flat so that it will lie 50 against the flat outer surface of the ear as illustrated at the open space 21 and accommodate a considerable swelling of the ear without causing the tag to pull on the opening 17 pierced in the ear, while the annular 55 position of the sides 10 and 11 caused by the scoring of the tag A along the line 18 positions the outer curved end 12 close against the edge of the ear so that it is of the same approximate shape as the outer 60 thin edge of the animal's ear and fits closely so that approximately no space is permitted between the edge of the ear and the tag and this prevents the ear from getting caught on anything which would have a tendency to 65 pull the tag out of place. The flat side 10

is of a desirable formation when the tag is in place. The tag A does not act to pierce the ear but is placed in position between the applying device described in my hereinbefore mentioned application, which cuts a sharp clean opening within the ear without tearing and therefore the irritation on the ear is much less than where the tag itself is used to pierce the ear. These features are of importance in my invention. 75

A feature of the invention which is of primary importance is the sealing of my tag to prevent it from being tampered with or removed without destroying the same. This is accomplished by the score or cut lines 16 and 18 in the tag A which weaken the tag at these points so that the tag can not be removed without breaking the same and thus my tag is self sealing by a very simple and effective means. This construction provides an inexpensive tag which is self sealing and can practically not be removed without destroying the same so that it is readily apparent that the particular construction and formation of my tag is of primary importance in my invention. 85

In accordance with the patent statutes, I have described and illustrated in the drawing a particular formation of a tag which illustrates one form of the invention but I 95 desire to have it understood that the drawings are only illustrative and that the invention can be carried out by other means and applied to other uses than those set forth within the scope of the following 100 claims.

I claim:

1. A cattle tag including a body portion formed of flat wire, a portion of the body of said tag extending in a straight line 105 to lie flat on the animal's ear with overlapping end members adapted to seal said tag and weakened portions formed in said tag to position said overlapping end members in an angular relation to said flat portion to form an enlarged portion for the swelling of the ear and to prevent the removing of the tag without destroying the same. 110

2. An animal marking tag including a body portion formed of flat wire, end members bent to form an enlarged portion on one end and a curved portion conforming with the edge of an animal's ear on the other end, said end members being adapted 115 to overlap adjacent the opening in the animal's ear. 120

3. A self sealing animal marking tag including a body portion formed of flat wire, end members bent to form an enlarged portion on one end and a curved portion conforming with the edge of an animal's ear on the other end, said end members being adapted to overlap, weakened portions 125 formed adjacent the end of one of said 130

members and at the portion adapted to conform with the edge of the animal's ear to cause said tag to break if it is bent to remove it from sealing position on the animal's ear.

4. A marking tag formed of strip material, transverse score lines extending across said material between the ends thereof to

permit said tag to be bent into closed position with one end to conform with the edge ¹⁰ of an animal's ear and the other end with an enlarged portion adjacent the portion of said tag extending through the ear and to prevent removal of the tag without breaking the same.

WARREN J. FRETZ.
